GAS GENERATOR

Henry Tobler, Jr., Yonkers, N. Y., assignor, by
mesne assignments, to Allied Process Corpora-
tion, New York, N. Y., a corporation of New
York

Application February 6, 1945, Serial No. 576,488

3 Claims. (Cl. 23—282)

1

This invention relates to the art of generating gas by reaction between a solid and a liquid. While the invention arose out of the demand for an improved means for generating gas in an emergency, it is not limited to use in such emergencies. Such an exigency is illustrated by the forced landing of an airplane. In this particular emergency it is desirable that equipment be provided including a gas generator which may be employed to inflate a signal balloon to assist in locating the position of the forced landing. A generator which is entirely satisfactory under these conditions must meet with extremely rigorous criteria. The element of time is important, since a balloon for example must be inflated in a matter of minutes rather than hours and the fewer the minutes the better. The construction of the generator itself and the equipment of which it forms a part must be so simple that there is no waste of time consumed in the assembling and operating of more or less complicated apparatus. The required volume of gas should be evolved very quickly. In many cases the evolution of the gas is the result of an exothermic chemical reaction, as for example, the reaction of various hydrides including hydrides of alkali metals and alkaline earth metals with water. The rapid evolution of the gas means the liberation of the heat of reaction within a matter of minutes. Unless the heat thus liberated and concentrated in a very short time interval, is adequately dissipated, the temperature of the apparatus will rise and become so hot that it cannot be readily handled. It is also desirable that the evolved gas should be as free as possible from entraining liquid, particularly when, as is often the case, that liquid is corrosive in nature. All of these factors and others present inter-related problems to the solution of which the present invention is directed.

In accordance with this invention, the foregoing factors are correlated and dealt with in a practical manner by providing apparatus in which the generation of gas takes place within a container, and under some pressure, but nevertheless what may be termed the "free generation" rate. That is to say, about as rapid generation as can be expected is that at which the gas would be formed from the reacting chemicals in open space, and this rate may therefore be termed the "free generation" rate. Such a rate will, obviously, be accompanied by a tendency of high temperature rise, as the heat of the reaction is liberated in the shortest period of time. In order to attain substantially the free generation rate,

2

and at the same time maintain the solid charge at a temperature below that at which it would be baked or coated with sludge, and also maintain the liberated gas sufficiently cool to prevent injury to the balloon, provision is made for the continuous washing of the solid and gas; for the maintenance of a suitable pressure not greatly exceeding barometric pressure; and for passageways or ducts for the generated gas to effect its removal without the development of excessive back pressure.

It is accordingly an object of the present invention to provide a generator having advantages including the following:

1. Simplicity of construction and operation.
2. Portability and minimum weight.
3. Evolution of a predetermined volume of gas rapidly, that is, during a minimum time period.
4. Evolution of said gas in a relatively cool condition.
5. Evolution of said gas relatively free from entrained liquid and therefore free from entrained by-products which may be corrosive, e. g., alkalies and alkaline earths.
6. Efficiency of gas evolution, i. e., production of a maximum quantity of gas from a minimum weight or volume of solid material.

For the sake of convenience the solid body which by reaction with liquid, generates the gas, will be identified generically as the "charge." This may be a salt-like hydride, e. g., a hydride of lithium or a hydride of an alkaline earth metal, or hydrides made from alloys of lithium and alkaline earth metals. The invention is not however limited to the use of any particular chemical nor of any particular liquid which reacts therewith, because the invention resides in the structural and functional features which are advantageous in connection with a considerable number of specifically different gas-generating chemical reactions between solids and liquids. Those structural features can be employed to advantage in connection with the generation of various gases, including not only hydrogen but also oxygen, nitrogen, hydrogen sulfide, ammonia, hydrocyanic acid and various other gases and vapors.

In appreciating the various features of the invention, it is necessary to bear in mind a number of important matters. The reaction between a solid material and a liquid to generate a gas by that reaction involves a surface reaction and is accompanied by the production of a by-product. For example, the reaction between a salt-like hydride of a metal and water or aqueous liquids produces not only hydrogen but also the hydroxide of the metal. Even though the

by-product may be soluble in the liquid, it tends to form or does form a coating on the hydride particles which retards and may entirely stop the reaction. Now if the particles of the solid reactant are continuously washed by the fresh liquid, fresh surfaces of reactant are continuously presented to the liquid and speed of reaction is thereby facilitated. If a more or less static body of liquid is contacted with the solid reactant, the concentration of by-product builds up and not only is the coating effect just mentioned experienced but also, according to the law of mass action, the reaction is slowed down by accumulation of a product of the reaction. Moreover, heat is frequently generated by the reaction and if the same body of liquid is exposed to the action of the solid reactant, the temperature of that liquid will rapidly increase and the temperature of the evolved gas will be correspondingly high.

On the other hand, if fresh, i. e., unreacted and cool bodies of liquid are continuously brought in contact with the solid reactant and the by-products, and liquid associated therewith continuously swept away, many of the advantages above listed may be obtained.

The present invention visualizes a lateral spreading out of the charge to a thin depth and contained and maintained within a bell or inverted cup. Now if that shallow inverted cup or dish be placed, while still inverted, in a liquid which reacts with the charge to produce a gas, it will be seen that the reaction is very rapid. Substantially all parts of the charge are immediately accessible to the liquid. The evolved gas must pass downwardly to escape below the depending edges of the dish, bell or cup. Assume that the charge is a salt-like hydride, e. g., lithium hydride and that the liquid is water. The reaction is

where ΔH is the heat of reaction. The gas in passing down through the liquid and then upwardly, heats the liquid and is cooled to an extent depending on the temperature of the liquid. If the charge is maintained within the bell or cup in such manner that there is opportunity for the free movement of gas, and liquid away from the reaction zone, the liquid in the immediate vicinity of the charge is displaced and its place taken by fresh, cool liquid, this action being facilitated by the turbulence produced by the rapid reaction and generation of gas. There is thus a continuous displacement or expulsion of liquid containing by-products and an intake of unreacted and cool liquid, accompanied by a sort of surging motion. Thus the gas is washed and cooled notwithstanding its rapid evolution, indeed that rapid evolution which normally would produce a hot gas in a more or less confined liquid, actually assists in producing a cool liquid.

Moreover, the movement of liquid toward and away from the charge, stale liquid away and fresh unreacted liquid toward the charge has a number of advantages in addition to producing a cool gas. The by-products which may be in the form of sludges, are removed. The surfaces of the reactant particles are washed and fresh surfaces presented to the reacting liquid. Thus continuity and rapidity of reaction are obtained. Rapidity alone is not enough because even a rapid reaction is ineffective if for any reason it is stopped too soon; and a surface reaction will be stopped too soon or retarded if the sur-

face becomes coated with a material which prevents access of reacting liquid to the surface of the reactant.

The production of a given volume of gas in a minimum time is therefore a function not only of inherent rapidity of reaction but also continuity of reaction. Surface area, i. e., active surface area, or more accurately the ratio of exposed active surface area of the solid reactant to the liquid is also important. The initial surface area may be made large by choosing particles having a selected range of sizes. However, if the surfaces become coated with unreactive sludges or by-products, the effective surface area soon decreases. Hence the necessity of washing the surfaces of the solid particles with the liquid reactant, removing by-products and bringing fresh surfaces of solid reactant into contact with unreacted liquid reactant.

In addition to securing the above mentioned basic operational or method advantages of rapid reaction, continuity of rapid reaction, generation of gas in a cool condition and efficiency of gas production, it is necessary to avoid apparatus features which are awkward or even impractical and in accordance with the invention, the beneficial and advantageous effects are obtained by structures which are compact, simple and portable.

The nature and advantage of the invention will be further apparent from the following further description taken in conjunction with the drawings in which

Fig. 1 is a diagrammatic view illustrating certain generic features of the invention;

Figs. 2 to 7 illustrate certain forms of the invention;

Figs. 8, 9 and 10 illustrate a somewhat modified form of the invention;

Fig. 2 is a plan view of the gas generator;

Fig. 3 is a vertical sectional view on the line 3, 3 of Fig. 2;

Fig. 4 is a vertical sectional view on the line 4, 4 of Fig. 2;

Fig. 5 is a perspective view of the charge container;

Fig. 6 is an elevational assembly view of the charge container, balloon and associated parts including a tube or conduit, serving as handle, for conducting the gas from the gas generator to the balloon;

Fig. 7 is a vertical sectional view showing the said tube or conduit and associated parts including a gas valve;

Fig. 8 is an assembly view analogous to Fig. 6;

Fig. 9 is a sectional view on line 9, 9 of Fig. 8 and

Fig. 10 is a perspective view of the gas generator with parts broken away.

Referring first more particularly to Figs. 1 to 5 inclusive the apparatus has a generally rectangular shape. This however is a matter of choice or manufacturing convenience and the apparatus may have any desired geometrical shape, for example, it may be cylindrical or hexagonal. The particular form of apparatus shown in the drawings for purposes of illustration includes a rectangular inverted cup or bell having a closed top 1, side portions 2a, end portions 2 and 4 and a bottom 5. The charge container is positioned within an outer shell having an open bottom portion 6a, a top 6 and side or skirt portions 7. The top 6 is closed except for an opening 13 which receives a tube or handle

75 8 connected thereto which serves to lead the

generated gas from the generator to a place of disposal. The sides 2a and ends 2 and 4 of the charge container may be in spaced relation to the shell 1. As shown in the drawing, however, the sides 2a have a close fit with the corresponding skirt portions of the shell so that the charge container is spaced from the shell only at the ends thereof as clearly shown in Figs. 1, 3 and 4. Whatever may be the particular spacing arrangements of the vertical side walls of the charge container, in relation to the opposed shell walls, at least a part of said container side walls should be spaced from opposed side walls of the shell. The charge container may be supported within the shell in any convenient manner, as for example, by means of plates 11 secured to the walls of the shell and having brackets 12 on which the charge container is supported.

Instead of reducing the depth of the charge to such a small dimension that, for a given weight or volume of charge, the lateral cross sectional area of the charge and consequently the lateral dimensions of the apparatus as a whole, would be extended to such an extent as to make the apparatus awkward or impractical to manipulate and transport, the beneficial effects which have been described above may also be obtained by restricting the lateral cross sectional area of the charge and the apparatus and by increasing the depth of the charge while at the same time rendering the charge readily accessible to liquid, as for example, by means of a reticulated or perforated structure of the charge container. For example, as illustrated in Figs. 1, 3 and 4 the ends of the charge container in spaced relation to the walls 1 of the shell have solid or imperforate portions 2 depending from the top 1 and also perforated portions 4 extending up from the bottom 5 to the imperforate end portions 2. The bottom 5 is also perforated or reticulated.

It will be understood that in assembling the apparatus the charge container is filled with a suitable gas-generating solid material which may be in general any solid material which generates gas upon contact with liquid. It may be, for example, a salt-like metallic hydride having in a typical case a particle size varying for example from about $\frac{1}{4}$ to $\frac{3}{4}$ inches. Lithium hydride may be taken as a specific illustrative example. Such material when properly prepared is inherently very reactive with water with the production of hydrogen gas and lithium hydroxide as a by-product. When the water has an acid reaction, as for example, in the case of sea water, the reaction is even more rapid than in the case of fresh water owing to the action of the acid of the water with the lithium hydroxide by-product. In using the apparatus it may be immersed in a liquid which reacts with the solid to produce gas after connecting to a gas collector or balloon as hereinafter more specifically described, so that the top 6 of the outer shell is approximately level with the surface of the liquid. Owing to the rapid evolution of gas and the development of back pressure in the balloon, the level of water within the shell is depressed so that it may be for example approximately at the point 3 shown in Fig. 1 which is about midway between the top 1 of the charge container and the bottom of the imperforate end walls 2. It is to be understood that owing to the vigorous reaction and development and evolution of gas and surging of water into and out of the charge container and shell, the hydrostatic level men-

tioned is not static but constantly fluctuating. Gas developed within the charge container must necessarily pass downwardly because the top 1 is closed and the end portions 2 imperforate. These end portions form a seal which compels the gas to pass through the water between the end portions 2 and the opposed walls 1 of the shell. As the reaction progresses and pressure in the balloon increases, thus tending to further depress the water level, within the shell, it may be desirable to further immerse the generator in the water to assist in overcoming this back pressure and in maintaining said seal.

In some cases it is possible to carry the perforated portions 4 all the way up to the top 1 and in some cases the side walls of the charge container, including those spaced from the shell, e. g., the walls 2, may be solid or imperforate all the way down to the bottom of said charge container. It has however been found preferably or highly desirable to have imperforate parts 2, for example, in addition to the perforated portions 4.

The vertical dimension of the imperforate or solid side walls of the charge container (which walls are spaced from the shell) e. g., the walls 2 of Figs. 1 to 5, has been found to be important especially where the chemical reaction which generates the gas is an exothermic one. When the dimension is too large, it has been found that there is inadequate washing of all parts of the charge with liquid with the result that in the upper part of the charge the particles become coated with a by-product of the reaction, e. g., a metallic hydroxide in the case of salt-like hydrides (such as lithium hydride, potassium hydride, calcium hydride, etc.). This coating prevents or greatly retards reaction, the more so as the coating becomes hardened by the heat evolved, and the efficiency and capacity of the generator is impaired.

When the dimension is too small, the gas escaping from the charge container is incompletely washed and the gas temperature correspondingly higher. A range of three quarters of an inch to one and one quarter inches ($\frac{3}{4}$ "- $1\frac{1}{4}$ ") is recommended in dealing with hydrides of the nature of lithium hydride. One inch has been found satisfactory. The length of the perforated portions 4 may be approximately equal to those of the imperforate portions. These dimensions are indicated as D¹ and D².

As above mentioned a condition of more or less turbulence exists within the charge container. The rapid evolution of gas causes the expulsion of liquid within the container accompanied by the by-products of the reaction, as for example, lithium hydroxide sludge in the case of lithium hydride. This water, including that which has reacted with the lithium hydride is of course more or less warm or hot as a result of the reaction. When expelled or forced out through the perforations, its place is taken by cool water. There is thus a surging of water into and out of the charge container accompanied by a constant washing or bathing of the surfaces of the particles of solid material. The by-product hydroxide which in the absence of such washing would accumulate on the surfaces of said material and also clog the free spaces between said particles, is continuously removed. Thus, fresh surfaces of the active solid material are continually brought into contact with unreacted cool liquid and rapidity and continuity of reaction is ensured with the evolution of gas in a relatively cool condition. It is desirable to avoid any filling up of

the free spaces between the particles so as to maintain a sufficient minimum free space to permit the free passage of gas and liquid out of the charge container and unreacted liquid into the said container. Any clogging or filling up of these spaces would tend to confine the gas within the container and the back pressure thus developed would force the liquid away from the particles and tend to bring the reaction to an end. It will be noted that the turbulence and washing action which has been described are effective in providing for the free passage of gas and liquid and in providing continuity as well as rapidity of gas evolution.

Provision is also made for permitting the generated gas to pass freely to the balloon without any undue restrictions in its path which would tend to raise the velocity too high, generate too high a back pressure in the charge container and also carry entrained liquid into the gas collector. The free space or area between the ends 2 of the charge container and the opposed walls 7 of the shell is therefore preferably made sufficient to guard against undue pressure drop and undue velocity of the gas. As an indication of a desirable condition, it may be recommended that this free space or area be chosen so that the gas velocity will not exceed about 150 feet per minute or about 2.5 feet per second. In the drawings the space between the end walls 2, 4 of the charge container and the opposed walls 7 of the shell is indicated by D3.

The space between top 1 of the charge container and the top wall 6 of the shell acts as a settling or separation chamber in order to remove particles of liquid from the gas so that the latter when delivered to the balloon may be in as dry a condition as possible. Here again it is recommended that this space be chosen so that velocity of gas therethrough does not exceed about 150 feet per minute or 2.5 feet per second. The vertical dimension of this space is indicated in the drawing by the symbol D4, and about 1 inch has been found satisfactory with generators having a maximum capacity of about 4 cubic feet of gas per minute. The distance D4 may advantageously be increased to decrease the velocity of gas therethrough below 150 feet per minute since the less the velocity, the better the separation of liquid.

To guard against the escape of gas, the skirt or side walls of the shell are preferably carried down a reasonable distance below the bottom 5 of the charge container.

The diameter of the tube 8 is also preferably controlled so as to prevent an undue pressure drop and further provide for the free passage of gas from the generator into the balloon and thereby further guard against the development of back pressure in the charge container which would tend to force liquid away from the solid material and interfere with continuity of the reaction. With a $\frac{3}{8}$ " I. D. tube a velocity of 660 F. P. M. is satisfactory, while for a 1" I. D. tube a velocity of 744 F. P. M. is satisfactory.

Coming now to the more specific structural details, the top and bottom walls 6 and 17 of the shell 1a may be secured to the side walls 7 thereof at the joints or shoulder portions 21 and 16. Referring to Fig. 4, the connection at 21 is permanent, while the bottom cover 17 is removable so that in operation the bottom of the shell may be entirely open for the free passage of liquid into and out of the charge container. The perforated portion of the end walls 4 of the latter

may be double walled as shown in Figs. 3, 4 and 5 comprising an inner perforated portion connected to an outer perforated portion at the joints 25. The bottom of the charge container may likewise be double walled as shown, the inner bottom wall being connected to the inner side walls at the joints 36 and the outer bottom wall being connected to the outer side walls at the joints 12. The purpose of the double walled structure is to aid in the cooling action of the liquid on the gas by slowing down somewhat the velocity of the gas passing out of the charge container while still maintaining free passage of gas and liquid into and out of said container.

Reference will now be made to the details of the structure for conducting gas from the generator to the balloon and the valve structure in the latter. This comprises the tube 8 having an annular shoulder or flange 10 near the bottom thereof which receives an annular raised lip 9 defining an opening 13 in the top 6 of the shell. The tube 8 is provided with a pin 49 extending diametrically across the tube 8 and secured thereto at the ends of said pin and cooperating with slot 37 in tube or sleeve 45 to form a bayonet joint. Within tube 8 there is a tube 60 provided with slot 48 through which said pin 49 extends. A gasket 14 is provided. The tube 60 has a smaller diameter than the tube 8 and the pin 49 prevents the tube 60 from falling out prior to the time when the tube 8 is connected to the gas generator.

The tube 8 carries at the top thereof detachable sleeve 45, the connection between tubes 8 and 45 comprising the flange 46 and gasket 47. The top edges of the tube 45 serve as the valve seat 43 for the valve 42 which is a solid hemispherical resilient body, as for example, rubber, normally held in closed position on the valve seat by resilient or rubber bands 44 passing over the top of the valve and secured to the tube 45 by means of the lashing 54. The nipple or neck 41 of the balloon is also secured to the tube 45 by lashings 55 and 56. An extension of lashing 56 provides cord 57 to which cap 58 is attached to the end of tube 45 when the balloon is filled and tube 45 disconnected from tube 8.

The tube 60 is perforated so as to maintain as far as possible the effective internal cross section of tube 8 and normally occupies a lower position than that shown in Fig. 7 and is brought into the raised position shown in that figure by the engagement of the bottom edges of said tube 60 with a pin 22 extending across the opening 13 defined by the annular lip 9 on the top of the shell 6.

In using the apparatus the tube 8 and its associated parts including the balloon 49 as shown in Fig. 7 are inserted through the opening 13 in the top of the shell until the flange 10 engages the gasket 14 on the lip 9. In this operation, the bayonet joint slot 37 on the tube 8, engages the locking pin 22, by rotation of the tube 8, thus securing the tube 8 to the shell of the generator. At the same time the vertically movable perforated tube 60 is raised into the position shown in Fig. 7 by engagement with said pin 22 thereupon raising or opening the valve 42. At the same time the seal cap 27 is removed from its sealing connection with the gasket 26C provided on flange 26a of the bushing 26 and drops to the top of the shell as shown in Fig. 3. It will be understood that the purpose of the seal cap 27 as well as the removable bottom cover 17 is to prevent access of moisture, to the interior of the

shell and charge therewith until the apparatus is in condition for use.

The way in which the seal cap 27 is automatically removed when the tube 8 is secured in place as above described, and the structure involved is as follows: The lip or flange 9 has a lower extrusion or bushing 26 carrying a flange 26a brazed or otherwise joined to the top 6 of the shell. To said bushing 26 are secured two diametrically opposite ears 26b, defining with the lower edges of said bushing 26 slots 29 which receive pin 27a on the seal cap and by means of which the said cap is normally held in sealing connection with the said bushing 26. The cap 27 also is provided with lugs 29a for use in initially mounting the cap on the bushing 26 in assembling the apparatus. When the tube 8 is inserted in the opening 13 and connection made by engagement of pin 22 in the slots 15 to make a bayonet joint by rotation of tube 8, the edges 8a of the tube 8 engage the pin 27a on the seal cap thus twisting the latter and this combined with the downward movement of the tube 8 removes said cap which then falls on the top of the charge container.

The tube 8 is provided with a grip 33 rotatably mounted thereon and reel 32 fixedly secured to tube 8 mooring line 34 of which is secured to swivel joint 34a. Lashing 56 is extended to form loop 59 which is also secured to swivel joint 34a.

The apparatus shown in Figs. 8, 9 and 10 differs from that in Figs. 2 to 7 in detail. The bottom cover 17 (see Fig. 8) is similar to that shown in Fig. 3 and is sealed to the shell 1a by means of a tear strip 83 removable by means of key 85 along score lines 82 and 82a. The sealing structure at the top of Figs. 8 and 9 differs from that shown in Fig. 3 because the tube 8 is not only secured to the top 6 of the shell but is also recessed within a removable cover 81 normally sealed to the shell by a tear strip 82, removable by means of key 84 along the score lines 86 and 86a. The space between the top 6 of the shell and the cover 81 and the side walls 88, 89 serves as storage space for the balloon and the valve attachments thereof. In the structure shown in Figs. 8, 9 and 10, therefore, all the equipment may be contained within a single package, whereas in the equipment illustrated in Figs. 2 to 7, the balloon and its associated equipment, including the tube 8 and so forth, must be stored in a package separate from the generator.

In Figs. 8, 9 and 10, the tube 8 has mounted thereon a reel 32 which carries the balloon mooring line 34. To the tube 8 is riveted by rivets 79 an annular flange or shoulder 78 carrying a gasket 77. The balloon nipple is secured by lashings 35 and 36 to a bushing 79 which carries the valve mechanism, this bushing having a valve body portion 71 carrying a valve seat 43. The valve 76 is provided with valve orifices 90, the valve plate 75 being normally held against the gasket 81 on seat 43 by spring 74 secured to a spring holder 81 which in turn is secured to the bushing 79 by means of bracket 73. The lower part of the valve body 71 carries a transverse

locking pin 72 which cooperates with bayonet joint 80 to connect the bushing 79 to the tube 8. The connection is effected by fitting the valve body 71 over the tube 8 and locking it in place by means of the pin 72 and the bayonet joint 80. The bottom cover 17 is of course removed for the purposes previously described.

The lashing 36 is extended to form the loop 59 attached to snap fastener 94 secured to swivel joint 34a which in turn is secured to mooring line 34. Line 57 which is also an extension of lashing 36 is secured to stopper 93 which may be inserted in valve body 71 after the balloon is inflated.

What is claimed is:

1. A portable apparatus for generating and supplying gas for inflation of signal balloons and the like, comprising an outer shell, a removable bottom for said shell, whereby the apparatus may be readily immersed in water when such bottom is removed, the top wall of said shell being provided with a gas escape opening, a charge container mounted in said outer shell and spaced from the top, side and end walls thereof, said charge container having a perforated bottom and having end walls, the lower portions of which are perforated while the upper portions of said end walls are unperforated, a detachable closure for said gas escape opening in the top of said outer shell, a gas escape tube, coupling means for coupling said gas escape tube to said gas escape opening, said gas escape tube being movable downwardly to engage said closure to detach it from the gas escape opening.
2. The combination as claimed in claim 1, wherein the coupling means for attaching the gas escape tube to the gas escape opening is of the bayonet slot type.
3. The combination as claimed in claim 1, wherein the perforated bottom and perforated side walls are made double, comprising inner and outer perforated members arranged parallel and close together.
